UNITED STATES PATENT OFFICE

ABRAM G. LAWRIE, OF ST. LOUIS, MISSOURI

RERAILER FOR CARS AND LOCOMOTIVES

Application filed May 31, 1930. Serial No. 458,538.

This invention relates to certain new and useful improvements in rerailers for cars and locomotives, the peculiarities of which will be hereinafter fully described and claimed.

The main objects of my invention are to provide an efficient practical rerailer for cars and locomotives; secondly, to provide such a rerailer adapted to operate in places where other forms of rerailer are impractical; thirdly, to provide a rerailing member adapted to be used on the outside of the track rails in combination with another member, either right hand or left hand, adapted to be used on the inside of said rails according to which side of the respective rail a derailed wheel is located; fourthly, to provide each of such members with a lateral bearing flange adapted to bear solidly upon the base flange of a rail inside of the rail spikes and to fit over the heads of said spikes and hold them from being loosened in the rerailing operation; fifthly, to compensate for the sinking of the rerailing member under the weight of the car or locomotive; and sixthly, to secure such a member in its adjusted position and automatically spike it to the adjacent tie.

In the accompanying drawing on which like reference numerals indicate corresponding parts,

Fig. 1 represents a plan view of a railroad track at a turnout switch with my rerailer members applied thereto;

Fig. 2, a bottom plan of my right inner member;

Fig. 3, an outside elevation of the same;

Fig. 4, a front or receiving end view and section of the rails on the line 4-4 of Fig. 1;

Fig. 5, an inside elevation of the same;

Fig. 6, a bottom plan of my double outer member;

Fig. 7, a side elevation of the same as applied to a rail;

Fig. 8, a front or receiving end view of my double outer member;

Fig. 9, a rear end view of the same on a rail in section on the line 9-9 of Fig. 1; and

Fig. 10, a vertical sectional view on the line 10-10 of Fig. 1 showing my self-spiking lever.

The numerals 11 and 12 designate respec-

tively rails of the main line track, and 13 and 14 the rails of a turnout switch track, and 15 the usual wooden ties supporting said rails in a road-bed of a railway.

Usually in cases of derailment both wheels are off the track rails and one wheel is off on the inside of a rail and the other wheel on the outside of the opposite rail, as indicated by dotted lines in Fig. 1. I have therefore provided a rerailing member 16 which is adapted to be adjusted on the outside of a track rail as shown in Fig. 1, and also provide a co-operating member 17 adapted to be adjusted on the inside of the opposite rail. These two members in such a case of derailment are adjusted either one a little ahead of the other, or directly opposite each other, as the circumstances of the case may decide.

The outer member consists of a body having an inclined portion 18 that widens upward from the front end to the rear end, and is provided at each edge with a groove 19 for the wheel flange. At the upper widened end of the inclined portion is located an upstanding horn 20 with its tapering point towards the front and its sides adapted to guide the wheel and deliver it upon the adjacent rail. The groove 19 next to the rail is so located that its lower end is a suitable distance from the rail, while the upper end has the groove substantially ending over the ball of the adjacent rail to deliver the flange upon the inside of said rail. Directly adjacent to each groove 19 in said body, is an inclined wall 21 connecting the gradually ascending groove with a top plate 22 adapted to rest on the top of a rail and provided with depending flanges 23 overhanging the inside of the rail near the ball and forming a passage with considerable clearance for the rail that it encloses.

On the side of the body portion is formed a lug 24 having a vertical face adapted to fit against the lower portion of the web of the rail opposite the depending flange, and having a lower face 25 that is adapted to bear on the top of the base flange next to the web and between the heads of the rail spikes at the edge of the base flange and the web. To provide this solid bearing surface on the base

flange, I cut out a groove on the lower portion of said lateral lug at 26 so as to just clear the heads of the spikes as shown in Figs. 8 and 9. The middle portion of the bottom of this member is inclined downward from the rail passage towards the center or otherwise rounded to compensate for the sinking of the rerailing member when the weight of the car or locomotive wheel is passing up the inclined portion.

On the bottom surface of the body at suitable spacing thereon to accommodate the space between the ties, I have provided horizontally extending fingers 27 projecting outward towards and under the adjacent base flange, as shown in Figs. 6, 7 and 10. These fingers assist in maintaining the member in its adjusted position with regard to the rail.

The depending flange 23 is provided with horizontal holes below the ball of the rail. Through these holes fastening devices are inserted to engage the underside of the ball and prevent dislodging the plate portion from the rail top. Such fastening means are shown as set screws 28 in two holes of each flange, and a double pointed hangar 29 (Fig. 7), one pointed end being inserted laterally into said hole and extending under the ball of the rail while the lower point is wedged under the base flange of the adjacent rail. This clamping hook is preferred when it can be used in a space between the ties, and when a tie interferes with its use the said set screws 28 are relied upon. As shown in Figs. 8 and 9, this passage for the reception of the track rail at each side of the middle inclined portion is wide enough to allow of placing the rerailing member over the ball of a rail in an inclined position and then turning said body downward till it rests upon the ties, and then sliding it laterally towards the rail to engage the said fingers 27 below the base flange, and bring the vertical face 24 of the lateral lug against the side of the web. In order further to maintain this adjustment, I provide recesses along the bottom of the body of the said member forming a lip 30 to be engaged by a hook bolt 31 passing under the base of the rail and through a hook washer 32 to which it is secured by a nut, as shown in Figs. 7 and 9. Thus the lateral lug is firmly held against the web of the adjacent rail.

In the inclined middle portion near the center thereof is formed a recess 33 (Fig. 10) near the middle of which is a bearing socket for a center pivot 34 which serves as a fulcrum for a lever 35 having at its ends downwardly projecting points 36 and 37 that pass through corresponding openings in the body and recess. The point 36 is forced into the tie below that end of the lever when the wheel passes up the inclined middle portion and its tread engages the lever. When the wheel reaches the upper end of the incline the upper end of the lever is depressed and the point 37

is forced into the tie below, while the point 36 of said lever is raised from engagement with its tie. The change of spiking engagement allows of a slight lateral adjustment of the upper end of the rerailing member and facilitates the transfer of the wheel from said member to its proper place on the adjacent rail. If desired, however, this self-spiking device may be dispensed with and the position of the rerailing member be maintained by the engagement of downward projecting points 39 at the front end of the body portion. These projections may engage the side of the tie as shown in Fig. 10, or be forced into the tie when the tie is otherwise located with regard to the said points. The rerailing member above described is preferably used always on the outside of the track rail, as shown in Fig. 1. Its body portion, flanges and laterally extending lugs adjacent to the flanges are preferably in duplicate so that one piece of double member, may be used on the outside of either track rail, according to the derailment of the wheels.

The member 17 that is used in connection with this outer member just described, is preferably pointed in its body portion and has a groove 40 at one side of an inclined portion 41 adjacent to a side wall 42 and top plate 43 which has a depending flange 44 and lateral lug 45 similar to those described for the outer member. The depending flange 44 has a double pointed hook 46 similar to 29, and the lug 45 is similarly grooved on its under surface to pass over the heads of the spikes, and bear upon the web and base flange in the same way as do these parts in the outer member previously described. Furthermore, it is preferred to use a hook bolt 47 (Fig. 2) engaging the recessed rib 48 near the middle of the rounded bottom of this inner member to hold the lateral lug in engagement with the adjacent rail, as shown in Fig. 4. This inner member is preferably tapering towards the rear to adapt it to be used at a turnout switch from the main line where a block similar to the outer member above described can not be readily used. As shown in Fig. 1 this tapering inner member is provided with a detachable point portion 50 extending into the diminishing space near the switch point, the upper surface of this extension is hollowed to match the groove and tread of the inner member to which it is loosely pivoted by a staple and pin or other suitable connection. Such loose pivotal connection as indicated in Figs. 1 and 3 and the rounding bottom of said extension, allow of a slight rolling movement laterally of the extension when the weight of the car or locomotive is transferred to the extension. The danger of breaking the point of the inner member is thus avoided and the delivery of the tread of the wheel upon the ball of the rail is readily made.

Where wheels have been derailed on the opposite side of the track from those indicated in Fig. 1, the double grooved member 16 is adjusted on the opposite rail. The co-operating member is always used on the inside of the rail, whichever side the derailment occurs, but the member 17 is made right and left as shown in plan view in Fig. 1 in order to accommodate this adjustment of the double member to either side of the track itself. Thus the member 16 is combined with a left hand cooperating member 17, or a similar right hand one as shown in Fig. 1.

While the preferred and practical arrangement of my rerailer is to use the member 16 with a left hand inner member 17, or a right hand duplicate thereof 17', it is possible in some cases of derailment to use together the left and right members 17 and 17' at the switch points, paired for wheels derailed close to said switch points. Such use of the tapering members is indicated in Fig. 1, but the preferred arrangement wherever practical is that described previously by which the double outer member is used with either a left hand member 17 or right hand cooperating member 17'.

I claim:

1. A rerailer comprising an outer grooved inclined member and a cooperating inner grooved inclined member adapted to be adjusted respectively to the outside and the gauge side of opposite track rails,—one member having a double pointed pivotally mounted lever adapted alternately to engage adjacent ties when a wheel passes over said lever, substantially as described.

2. A rerailer comprising an outer grooved inclined member and a cooperating inner grooved inclined member adapted to be adjusted respectively to the outside and the gauge side of opposite track rails,—one member having a recess in its inclined portion, and a lever pivotally mounted in said recess and having downwardly projecting points adapted alternately to engage adjacent ties under pressure of a wheel passing up the inclined portion, substantially as described.

3. A rerailer comprising an outer member and a cooperating inner member adapted to be adjusted respectively to the outside and the gauge side of opposite track rails,—one member having an inclined middle portion with side grooves and widening towards the top and having an upstanding guiding horn at the top, and the other member having a detachable point with a rounded bottom adapted to roll toward the rail and deliver a wheel upon said rail when said guiding horn exerts a lateral pressure on the other wheel on the same axle in guiding the latter wheel to the adjacent rail, substantially as described.

4. A rerailer comprising a grooved inclined member having a depending flange adapted to overhang the ball of a track rail

and a side lug having a lateral bearing face adapted to bear on the web on the opposite side of said rail and also having its lower face grooved upward adapted to bear on the adjacent base flange and over the heads of the rail spikes,—said depending flange having a horizontal hole below the ball of the rail, and a vertical hook having two horizontal ends adapted respectively to be mounted in said flange hole and to engage the lower surface of the base flange of said rail and secure the adjusted position of the member of said rail, substantially as described.

5. A rerailer comprising two members adapted to be disposed respectively on the outer side and the gauge side of opposite track rails,—said members having their bottoms rounded downward away from the respective adjacent rail and recessed near the middle and having fingers extending horizontally towards the adjacent rail and adapted to bear on the underside of the base flange thereof between the ties, and a hook bolt engaging the recessed bottom and passing under said base flange, and provided with lock nut and hook washer to hold said fingers in their engagement with the base flange, substantially as described.

6. A rerailer comprising two members, one member having a grooved inclined surface with a depending flange and a guiding upstanding horn and adapted to be adjusted on the outside of a track rail and the other co-operating member having a grooved inclined surface and having a detachable extension loosely pivoted thereto and having a rounded bottom and adapted to fit between a main track rail and a turnout track near a switch point,—both said members having depending flanges and adjacent lateral grooved lugs, said lugs having a vertical face and grooved lower face adapted to bear respectively against the web and base flange on the opposite side of the respective rail from the said depending flange, and fastening means for securing said members in their adjusted positions on their respective track rails, substantially as described.

7. A rerailer comprising two members adapted to be disposed respectively on the outside and the inside of adjacent track rails, one member being pointed to fit between a main line rail and a turnout track rail near the switch point,—said member having a grooved inclined portion for wheel tread and flange, and a lateral lug having a vertical bearing face and a lower grooved bearing face adapted to bear respectively against the web and the base flange inside the rail spikes, the opposite side of said member having a vertical face recessed for an adjacent fish plate and having a lower inner groove for receiving the heads of rail spikes, and fastening means for both said members, substantially as described.

8. A rerailer comprising two members both having inclined grooved surfaces for wheel tread and flange and adapted to be adjusted respectively to the outside and the gauge side of opposite track rails and provided with lateral lugs below the ball of the adjacent rail, said lugs having a vertical face bearing against the web of the rail and a lower grooved face bearing on the base flange and above the rail spikes, and a rounded bottom bearing on the ties, the front end of each member having downwardly projecting points adapted to engage the face or top of the adjacent tie according to its location with regard to said member, substantially as described.

9. A rerailer comprising a body portion having a lateral lug adapted to slip under the ball of a rail and having a vertical face to bear against the lower portion of the rail web and also a lower face provided with a groove to clear the spike heads and forming a bearing portion to rest on the rail base flange between the spikes and the web.

10. A rerailer comprising a body portion having a top plate to rest on top of a rail, the plate having a depending flange overhanging one side of the rail near the ball, and said body portion provided with a lug along its side adapted to slip under the other side of the ball opposite said flange, said lug having a vertical face to bear against the lower portion of the web on the opposite side of the rail from the depending flange and also having a grooved underface adapted to clear the spike heads and form a bearing on the base flange of the rail between the spike heads and the web.

In testimony whereof I have affixed my signature.

ABRAM G. LAWRIE.
